SULFURIZING TERPENES

John J. Alexander, Munster, Ind., assignor to
Standard Oil Company, Chicago, Ill., a corpora-
tion of Indiana

Application April 30, 1948, Serial No. 24,285

8 Claims. (Cl. 260—139)

1

This invention relates to an improved method of sulfurizing terpenes with elemental sulfur.

Terpenes have heretofore been sulfurized with elemental sulfur by mixing the terpene with sulfur and heating the mixture to the desired reaction temperature. Another method heretofore employed is to heat the terpene to the reaction temperature while adding the required amount of sulfur thereto in incremental amounts. These methods of sulfurizing terpenes are not satisfactory in that it is extremely difficult to regulate the temperature or to control the rate of reaction due to the exothermic nature of the reaction. The incremental or continuous addition of sulfur to the reaction involves many difficulties since the light terpenes reflux at the reaction temperature and the condensate impedes the addition of dry sulfur. Because of difficulties encountered in controlling the exothermic reaction when terpenes are sulfurized by the methods just described, the sulfurized terpenes are very dark in color.

An improved method of sulfurizing terpenes with elemental sulfur is described and claimed in a copending application of Roger W. Watson, Serial No. 665,291, filed April 26, 1946, which issued as Patent No. 2,445,983 on July 27, 1948, in which terpenes are sulfurized by adding liquid terpenes to molten sulfur. In this method a small amount of the terpene is introduced into the heated sulfur as a diluent during the viscous sulfur stage encountered in heating sulfur to the reaction temperature of about 375° F. to about 400° F. This viscous sulfur stage is encountered at a temperature of about 330° F. The necessity of heating a small amount of terpene with the sulfur through the viscous sulfur stage to the reaction temperature of about 340° F. to about 380° F. results in a darkening of the finished sulfurized terpene.

It is an object of the present invention to provide a method of sulfurizing terpenes by introducing terpenes into molten sulfur which will avoid the darkening of the sulfurized terpenes.

It is another object of the present invention to provide a method of sulfurizing terpenes in which the exothermic reaction can be controlled and a sulfurized terpene product of improved color obtained.

Other objects and advantages of the present invention will become apparent from the following description thereof read in conjunction with the accompanying drawing, which is a flow diagram of a preferred method of carrying out the present invention.

2

I have discovered that the foregoing objects can be attained by a method of sulfurization in which the terpene is added in the liquid phase to a body of molten sulfur at a certain optimum temperature, maintained in a non-viscous condition by the addition of a small amount of liquid terpenes which are not sulfurized, under the sulfurization conditions, or which if sulfurized, are readily desulfurized under the deactivation conditions hereinafter described, and which have boiling points below that of the desired sulfurized terpene. A suitable material is the distillate obtained in the fractionation of terpenes previously sulfurized by the addition of liquid terpenes to molten sulfur as hereinafter described. The distillate comprises essentially unsulfurized terpenes, such as para-cymene and paramethane, and a very small amount, namely less than about 2%, of low-boiling sulfurized terpenes. The terpenes which can be sulfurized by the herein described method include monocyclic, bicyclic and acyclic terpenes, as well as polyterpenes. Examples of species falling within these classes of terpenes are pine oil, turpentine, alpha-pinene, beta-pinene, alpha-ocimene, fenchene, bornylenes, menthadienes, such as limonene, dipentene, terpinene, terpinolene and 2,4,(8)-p-menthadiene, sesquiterpenes, diterpene, and polyterpenes having the general formula $(C_5H_8)_n$. Mixtures of such terpenes can also be employed in the invention. In accordance with the present invention, elemental sulfur is stirred at a temperature above its melting point, for example at a temperature of from about 325° F. to about 400° F., and preferably at a temperature of from about 340° F. to about 330° F., and the terpenes slowly added in the liquid phase to the molten sulfur.

Depending upon the intended use of the sulfurized terpene, any amount of sulfur can be employed in the sulfurization of the terpene by the herein-described method. However, for the preparation of sulfurized terpenes as a lubricant additive, the sulfur-terpene reaction mixture should contain from about 25% to about 50%, and preferably about 40% by weight of sulfur, and from about 50% to about 75%, and preferably about 60% by weight of the terpene.

Sulfur, when heated to a temperature of from about 300° F. to 340° F., enters a so-called "viscous stage." To facilitate adequate stirring during this stage, when the molten sulfur reaches a temperature of from about 300° F. to about 340° F., and preferably from about 300° F. to about 325° F., a small amount, namely from about 3%

to about 10%, and preferably from about 5% to about 7% by weight based on the sulfur of a distillate from sulfurized terpenes as hereinafter described, is added to the molten sulfur and the temperature then raised to the desired reaction temperature, namely 340° F. to about 400° F., and the terpene to be sulfurized added.

The sulfurized terpenes contain some active sulfur, as evidenced by the darkening of a copper strip submerged in about 0.5% solution of the sulfurized terpenes in a hydrocarbon oil maintained at a temperature of about 210° F. For certain uses, such as lubricating oil additives, the presence of such active sulfur compounds in the sulfurized terpenes is undesirable. These so-called active sulfur compounds can be deactivated by treating the same with an alkali metal sulfide, such as sodium sulfide or with a mixture of an alkali metal sulfide and a small amount of an alkaline material such as, for example sodium hydroxide.

After the sulfurization reaction is completed, which will take about 5 minutes to about 60 minutes or more, and usually about 15 minutes, the sulfurized terpene is rendered non-corrosive by deactivation by the addition of an alkali metal sulfide, such as sodium sulfide, preferably added as an 18% aqueous solution. It will be understood that the time of sulfurization is dependent largely upon the rate of refluxing and other cooling means for controlling the exothermic reaction. During the deactivation stage the reaction mixture is maintained at a temperature from about 200° F. to about 260° F., and preferably at about 230° F. It is desirable during the deactivation stage to maintain the reaction mixture under a pressure sufficient to retain the light ends of the product, usually a pressure of about seven pounds will be found to be sufficient for this purpose. While it is desirable to carry out the deactivation at the preferred temperature of about 230° F., and a pressure of about seven pounds, higher or lower temperatures and pressures may be employed. After the sulfurized terpene reaction product is deactivated, such as by treatment with the sodium sulfide, the reaction mass is permitted to separate into an upper layer comprising the sulfurized terpenes and a lower layer comprising sodium polysulfide solution. After the sodium polysulfide solution layer is separated from the sulfurized terpene product the latter is washed at a temperature of from about 200° F. to about 250° F., and preferably at about 220° F. with a 20% sodium chloride solution. The brine solution is then settled and drawn off. The washed deactivated sulfurized terpene product is then filtered and again washed with a 20% sodium chloride solution to remove the last traces of alkali metal polysulfide from the sulfurized product. If desired, the sulfurized terpene product can then be flash distilled, preferably under reduced pressure, to remove any unreacted hydrocarbons or slightly sulfurized lighter terpenes, preferably using an inert gas, such as nitrogen for stripping. In order to avoid the darkening of the sulfurized terpene product, it is essential that the material be held at a temperature of from about 250° F. to about 350° F., and preferably at about 300° F., for a period of time no longer than about 30 to 35 minutes.

The following description of sulfurizing a mixture of terpenes comprising from about 60% to 65% menthadienes of which a major proportion is dipentene, and small amounts of terpinoline,

terpenes and 2,4(8) menthadienes and about 30% to 35% para-cymene and para-menthane, is given by way of example only and is not to be construed as limiting the scope of the invention.

Referring to the accompanying drawing, elemental sulfur forming about 40% by weight of the sulfurized reaction mixture, is introduced from sulfur storage tank 10 through a line 11 to the jacketed reactor 12 provided with a jacket 13, heating means such as superheated steam introduced through a line 14, and a temperature control means 15. If desired, the reactor 12 may be provided with a Dowtherm boiler to supply the necessary heat. The jacketed reactor 12 is provided also with cooling means such as, for example, water inlet and outlet 16 and 17, respectively. After the required amount of sulfur is added to the reactor 12, it is heated to a temperature of from about 300° F. to about 330° F., at which time about 5% to about 7% by weight of a diluent, the composition of which is hereinafter described, from distillate storage tank 18 is introduced, in the liquid phase, into the reactor 12 through the line 19, pump 20 and lines 21 and 22, and the mixture stirred or agitated by means of stirrer 23 or other suitable means. The distillate (herein referred to as diluent) from storage tank 18 comprises essentially unreacted or unsulfurized terpenes, such as para-cymene and para-menthane, together with a small amount of sulfurized low-boiling terpenes resulting from the fractionation of terpenes previously sulfurized in accordance with the present invention as hereinafter described. While it is advantageous to employ as the diluent, the distillate fraction such as described, obviously the present invention can be practiced by employing as a diluent preceding the viscous sulfur stage, small amounts of terpenes from any source and which are not readily sulfurized. After the addition of the diluent to the reactor 12, the temperature of the contents of the reactor is increased to a temperature of about 340° F.-380° F., and terpenes, in the liquid phase, from terpene storage tank 24 introduced into the reactor as rapidly as possible through pump 20 and lines 21 and 22. The quantity of terpene employed amounts to about 60% by weight of the sulfur terpene reaction mixture. During this period the temperature within the reactor is maintained within the range of from about 340° to 380° F., suitably by means of a reflux condenser 25. The hydrogen sulfide formed is vented from the reactor 12 through a line 26.

The sulfurized terpene mixture is then deactivated by treatment with an 18% aqueous solution of sodium sulfide from tank 27 introduced into the reactor 12 via pump 28 and line 29. From about 10% to about 20%, and preferably 14% to 15% by weight of sodium sulfide is usually sufficient to deactivate the sulfurized terpene product. During the time the sulfurized terpene reaction product is being deactivated with the sodium sulfide, a temperature of about 230° F. is maintained in the reactor by passing steam into the jacket 13. The mixture of sulfurized terpene reaction products and sodium sulfide is stirred at the proper temperature for a period of about two hours while maintaining a pressure of about seven pounds upon the reactor to retain the light ends. At the end of the two hour deactivation period, the reaction mass in reactor 12 is permitted to stratify into an upper layer comprising the deactivated sulfurized terpene product, and a lower layer of sodium polysulfide

solution, and the latter drawn off through lines 22 and 30 to a sodium polysulfide storage tank 31.

After the sodium polysulfide solution is withdrawn from the reactor 12, the deactivated sulfurized terpene is washed with a 20% sodium chloride solution introduced into the reactor 12 from tank 32 through pump 33 and lines 34 and 29. The washed deactivated sulfurized terpene product is then settled and the sodium chloride drawn off through lines 22 and 35 to the sewer.

The solid sodium polysulfide remaining in the washed deactivated sulfurized terpene, together with any other solid or colloidal impurities, are removed by introducing the sulfurized terpene via lines 22 and 36 and pump 37 to a suitable filter 38, which may be a Sparkler type filter. Filter 38 is maintained, by suitable means, at a temperature of about 320° F. and operated at a pressure of about twenty pounds per square inch. It has been found that a filter rate of 12½ gallons per hour per square foot is suitable. Lower or higher pressures or temperatures can of course be employed but with some sacrifice in efficiency.

The filtrate from the filter 38 is passed via line 39 to a wash drum 40, provided with stirring means 41 wherein the filtered sulfurized terpene is washed one or more times with a 20% sodium chloride solution from tank 32, via pump 33 and lines 34 and 42, to remove the last traces of sodium polysulfide. The sodium chloride solution in wash tank 40 is withdrawn via line 43 to tank 44. The used sodium chloride solution may be dumped to the sewer, or if a plurality of washes are used, the last wash may be recycled to the wash drum for the washing of the next batch.

The washed filtered sulfurized terpene from wash tank 40 is passed via pump 45 and lines 46 and 47 to a preheater 48 wherein the sulfurized terpene is heated to a temperature of about 390° F., and then introduced into a stripping tower 49, wherein the heated sulfurized terpene is flash distilled at about 50 mm. pressure and with sufficient nitrogen purge gas, introduced from nitrogen supply tank 50 via line 51, to reduce the sulfurized terpene product to a bottoms fraction having the desired sulfur content. If desired, a portion of the nitrogen from tank 50 may be introduced via lines 51 and 52 to line 47 and introduced into the stripping tower 49, together with the sulfurized terpene. The stripping tower 49 may be provided with heating and/or cooling coils 53.

The amount of nitrogen used is that necessary for maintaining agitation within the stripper 49 and for removing the light ends in the bottoms. An overhead fraction is taken from the stripper 49 via line 54 and condenser 55 to a separator drum 56, from which uncondensables are withdrawn via vacuum pump 57 and line 58. Unreacted terpenes and sulfurized low-boiling terpene products recovered as overhead from the stripping tower 49 are removed from separator drum 56 via pump 59 and line 60 to the storage tank 18.

The unreacted terpenes, and sulfurized low-boiling terpene products in tank 18, are recycled through line 19, pump 20, and lines 21 and 22 to the reactor 12, as a diluent for the molten sulfur, as hereinbefore described.

The bottoms from the stripper 49, comprising essentially the desired sulfurized terpenes are withdrawn via pump 61, passed through a cooler exchanger 62 and through line 63 to storage tank 64.

The filtered, sulfurized terpene, after the sodium

chloride wash in wash drum 40, may be used as a lubricant additive. It is desirable to remove the light ends of the product and concentrate the bottoms to a sulfur content of from about 30% to about 50%, and preferably about 40%. Sulfurized terpenes, preferably sulfurized dipentene having a sulfur content within this range, are suitably employed as lubricant additives to inhibit corrosion and as extreme pressure agents.

By conducting the sulfurization of terpenes in the manner herein described, heating sulfurizable terpenes in the presence of sulfur at elevated temperatures over prolonged periods is avoided. This avoids the possible formation of dark colored sulfurized terpene products with the result that the sulfurized terpenes obtained by the present invention are of improved color. Other advantages obtained are that the heat taken up by the incoming terpene such as diventene helps to control the speed of reaction. Furthermore, introducing the terpene at substantially reaction temperature results in substantially instant sulfurization so that substantially no polymerization or resinification takes place.

While I have described in detail the preferred embodiment of my invention it should be understood that the invention is not limited to the details hereinabove set forth, except as defined by the appended claims.

I claim:

1. In the method of sulfurizing terpenes wherein elemental sulfur is heated to a molten temperature of from about 325° F. to about 400° F., and a sulfurizable liquid terpene introduced into said sulfur and the mixture maintained at said temperature for a time sufficient to complete the sulfurization of said terpenes, the improvement comprising heating the sulfur to a temperature of from about 300° F. to about 340° F., introducing into said heated sulfur a small amount of a liquid consisting of terpenes which are not sulfurized under said sulfurization conditions and which boil below the boiling point of the desired sulfurized terpene, whereby said molten sulfur is maintained in a fluid state, increasing the temperature of the mixture to about 340° F. to about 400° F., and introducing into said molten sulfur the sulfurizable liquid terpene to be sulfurized.

2. In the method of sulfurizing terpenes wherein sulfur is heated to a molten temperature of from about 325° F. to about 400° F., and sulfurizable liquid terpenes introduced into said molten sulfur and the mixture maintained at said temperature for a time sufficient to effect the sulfurization of said terpenes, the improvement comprising heating the sulfur to a molten temperature of about 300° F. to about 325° F., introducing a small amount of a liquid consisting of terpenes which are not sulfurized under sulfurization conditions and which have boiling points below that of the desired sulfurized terpene product, whereby said molten sulfur is maintained in a fluid state, increasing the temperature of the mixture to a temperature above about

340° F. but below about 400° F., introducing sulfurizable liquid terpenes to be sulfurized in said molten sulfur and maintaining said temperature for a time sufficient to substantially complete the sulfurization of said last named terpenes.

3. The method of sulfurizing terpenes as described in claim 2 in which the sulfurizable terpenes to be sulfurized comprise essentially dipentene.

4. In the process of sulfurizing terpenes with elemental sulfur wherein elemental sulfur is

heated to a temperature above its melting point but below about 400° F., a mixture of sulfurizable and unsulfurizable liquid terpenes introduced in said molten sulfur and maintained at said temperature for a time sufficient to substantially complete the sulfurization of said sulfurizable terpenes, the mixture of sulfurized terpenes and unsulfurized terpenes fractionated to obtain a bottoms fraction consisting essentially of substantially entirely of the sulfurized terpenes, and a distillate fraction consisting essentially of lower boiling unsulfurized terpenes and a small amount of low-boiling sulfurized terpenes, the improvement comprising introducing a small amount of said distillate into a subsequent batch of molten elemental sulfur heated at a temperature of from about 300° F. to about 325° F., increasing the temperature of the mixture of molten sulfur and distillate to above 350° F., but below about 400° F., and introducing sulfurizable liquid terpenes in said mixture, maintaining the reaction mixture at such a temperature above 350° F., but below 400° F. for a time sufficient to substantially complete the sulfurization of said last named terpenes.

5. The method of sulfurizing terpenes as described in claim 4 in which the sulfurizable terpenes are a mixture of menthadienes and the recycled distillate consists essentially of unsulfurized cymene and menthane.

6. The method of sulfurizing terpenes as described in claim 4 in which the mixture of sulfurizable and unsulfurizable liquid terpenes are a mixture comprising a major proportion of dipentene, and small amounts of terpinoline, 35 2, 4, (8) menthadienes, para-cymene and para-menthane and the recycled distillate consists essentially of unsulfurized para-cymene, unsulfurized para-menthane and a small amount of low-boiling sulfurized terpenes distillable at a 40 temperature of about 300° F. at about 50 mm. pressure.

7. The method of sulfurizing terpenes comprising heating a body of elemental sulfur to a temperature of about 300° F. to about 325° F., 45

adding a small amount of terpenes consisting essentially of para-cymene and para-menthane, which are not sulfurized under sulfurization temperatures of 340° F. to 380° F., heating the mixture to a temperature of 340° F. to about 380° F., adding a mixture of sulfurizable and unsulfurizable terpenes to the heated mixture, maintaining the mixture at a temperature of about 340° F. to about 380° F. for a time sufficient to substantially complete the sulfurization of the sulfurizable terpenes in said terpene mixture, reducing the temperature of the reaction mass to a temperature of from about 200° F. to about 250° F., adding an alkali metal sulfide to the reaction mixture to remove corrosive sulfur compounds therefrom in the form of polysulfides, separating the polysulfides from the reaction mixture, distilling the alkali metal sulfide-treated reaction product at a temperature of about 300° F. at about 50 mm. pressure, to obtain a bottoms fraction comprising essentially a sulfurized terpene product containing from about 30% to about 50% sulfur and a distillate fraction comprising essentially low-boiling unsulfurized terpenes and low-boiling sulfurized terpenes, and recycling a portion of said distillate to a body of molten sulfur heated at a temperature of about 300° F. to about 325° F. to maintain said body of sulfur in a non-viscous fluid state.

8. The method of claim 7 in which the sulfurizable terpenes comprise essentially dipentene.
